UNITED STATES PATENT OFFICE

ANTOINE VÉRICEL, OF BALDWIN, NEW YORK, ASSIGNOR TO DOEHLER DIE-CASTING CO., A CORPORATION OF NEW YORK

DESIGN FOR A RADIOCABINET OR THE LIKE

Application filed September 14, 1929. Serial No. 32,761. Term of patent 3½ years.

To all whom it may concern:

Be it known that I, ANTOINE VÉRICEL, a citizen of the Republic of France, and a resident of Baldwin, in the county of Nassau and State of New York, have invented a new, original, and ornamental Design for Radiocabinets or the like of which the following is a specification, reference being had to the

accompanying drawings, forming part thereof, wherein—

Fig. 1 is a front view of my new design, and Fig. 2 is a side view thereof.

I claim:

The ornamental design for a radiocabinet or the like, as shown.

ANTOINE VÉRICEL.
